GUN SIGHT

Stephen H. Crossman, St. Joseph, Mich.

Application June 26, 1944, Serial No. 542,216

12 Claims. (Cl. 33—58)

(Granted under the act of March 3, 1883, as amended April 30, 1928; 370 O. G. 757)

1

The invention described herein may be manufactured and used by or for the Government for governmental purposes without the payment to me of any royalty thereon.

The invention relates to sights suitable for use on ordnance or for other purposes and has for an object to offer a novel, small, simple, and inexpensive mount having important functional advantages.

It is a special further aim to present a construction particularly adapted to the use of an optical device capable of producing collimated rays of light representing the image of the target, or a telescopic image.

The invention in its present embodiment is designed so as to be applicable to use on firearms, and small caliber ordnance, but has capabilities of adaptation to more extensive use including heavy ordnance, if necessary, or desirable. As shown, it is designed for application particularly to small arms such as a rifle, mortar, or rocket launcher, and in the specific form presented is for use on the rifle when employed for launching grenades or the like, or on a rocket launcher or mortar for direct fire, where much higher trajectories are involved for usual ranges than are involved in the use of the ball cartridge at the same ranges.

It is an important aim of the invention to present a sight mount which may be produced almost entirely from sheet metal stampings, yet with dependable sight functions, and free from objectionable liability of derangement incident to ordinary army service use.

It is a special purpose to give a sight which will be extremely simple in function as to adjustment or setting for specific ranges, so that enlisted personnel will have no difficulty in obtaining accurate and proper settings for the usual ranges involved in the use of a sight on weapons of the character indicated.

It is a salient attainment of the invention that it may be quickly changed as to calibration, to co-ordinate its function with various kinds of ammunition having differing trajectory characteristics. That is to say, projectiles usually fired may be of different weights, and different propellant components, according to the requirements of combat which have been provided for and one would ordinarily have a higher trajectory than

2

another, so that an angular setting of the sight for one would not give the same range with other ammunition.

It has also been proposed to use for shells of the same bursting characteristics, a series of different propellant charges appropriate to short, medium, or long range firing, and each having its special trajectory forms.

It has therefore been an aim of the invention to enable the provision of range scales on the sight appropriate to the several forms and in such manner that they may be selected alternatively and used effectively by the soldier, either as interchangeable scale plates or as alternative

scales on a single dial plate, one to be selected and used according to the particular ammunition in use at the moment. This feature also enables the use of the same manufacture on rifles for grenade launching, adapted to the single service propellant cartridge M3, and to the same with the "vitamin pill" auxiliary cartridge of propellant, set in or at the tail of the grenade shell; and to use on the popularly named "bazooka" or rocket launcher, as well as other weapons, which may include the development of Stokes type mortars, either in their conventional use or in the expected development thereof to from-the-shoulder firing, and other low or high elevation use of the mortar. The same feature also will enable the ready application of the device to use on larger caliber ordnance should it appear desirable, by the provision of the special scale plate required for the particular gun and a specific ammunition therefor.

It is a highly important aim of the invention to obviate the need for separate front and rear sights on weapons such as mortars, rocket launchers and the like where unusually high trajectories in relation to range are involved. In such cases the front sight would have to be extremely bulky for a given scale of ranges, and it would not be practicable to include a satisfactory full scale of ranges without objectionable interference with handling and shipment of the weapon equipped with effective front and rear

sights. My invention, on the contrary, enables the use of a single small device, which may be mounted in the position of the rear sight only, and will enable more accurate laying of the weapon.

Additional objects, advantages and features of

invention reside in the construction arrangement and combination of parts involved in the embodiment of the invention, as will be apparent or understood from the following description and accompanying drawings, wherein

Figure 1 is a fragmentary side elevation of a rocket launcher on which my invention is incorporated;

Figure 2 is a rear view of the sight;

Figure 3 is a horizontal section on the sight axis of Fig. 2;

Figure 4 is a section on the line 4—4 of Fig. 2;

Figure 5 is a detail top view of the receiver;

Figure 6 is a plan of the pivot base of the range arm;

Figure 7 is a section on the line 7—7 of Fig. 6;

Figure 8 is a plan of a modified base plate, and interchangeable dial;

Figure 9 is a section on the line 9—9 of Fig. 8;

Figure 10 is a plan of the blank for the eyepiece mounting.

Referring more particularly to the drawings, there is shown a portion 15 of a tube or barrel, which may be that of a rocket launcher, although with appropriate elevation scales on my invention the barrel might be that of a rifle or the tube of a mortar.

My sight device is applied permanently to the launcher barrel or tube, although, as will appear, a base element only may be permanently attached to the left side of a barrel while the remaining sight parts are applied when required, making it particularly valuable for use on rifles, where occasional use of a grenade launcher on the rifle is intermittent by extensive use of the arm with ball ammunition. The sight includes a vertical base plate 16 and lower bracket arm 17, formed integrally, the base plate being a planiform part with a generally sector-shaped central area 18, but being extended below and above to parallel boundaries 19 and 20 respectively. From the lower boundary, the bracket part 17 is extended and bent sharply on the boundary 19 through an angle of approximately 125 degrees, so as to extend upward to the right at an angle to enable its ready attachment to a barrel or tube. The extension 21 of the upper part of the plate may be left in the plane of the sector portion where the device is to be attached to a large tube such as that of a rocket launcher and for rifles may be bent to the right so that the planiform body of the plate may lie flush with the face of the stock, which would be opened to allow placement of the device. In the present instance the extremity of the arm 17 is attached as by spot welds, to the under surface of the tube 15, while the extreme upper edge of the planiform vertical plate is laid on a tangent to, and spotwelded to, the left side of the tube.

The plate 16 is formed with an aperture 22 at the center of the sector area and an arcuate concentric sector edge 23 extends to the right beyond the extension 21 and bracket arm 17. A smaller concentric approximately semi-circular base ear 24 is formed on the left side of the plate 16. On the upper part of the sector area 18 near the edge 23 a scale 25 of elevations measured in hundreds of yards is marked on the base plate in a concentric series of numbers denoting respective ranges. The values are proportionate to the order of the units marked, beginning at the bottom of the scale.

An elevation or range arm 26 is provided, consisting of a resilient, planiform, sheet metal plate, of the same radial dimension as the sector area

18, and with a centrally apertured pivot base 27 alined with the aperture 22 and ear 24, but of much less extent angularly than the sector area 18. It is secured pivotally to the base plate by a rivet or screws 28 and 30 engaged in the axial apertures of both. The range arm has a radial upper edge portion 29 extending through the arc on which the scale 25 is formed, and an out-turned ear or stop 30 is struck from the material of the plate 16 to engage an upper edge part of the elevation arm 26 when at the upper limit of its movement with respect to the scale 25. A similar lower stop 31 is struck from the plate 16 to engage the lower edge of the arm 26 when the top edge 29 of the latter is at zero elevation of the scale 25. The angular dimension of the elevation arm 26 may be varied, but is at least sufficient to cover the entire scale 25 except the last mark thereon when the arm is at the upper limit of its movement.

Below the scale, and within the sector area, a series of indentations 32 are formed in the plate 16 concentric with the aperture 22 spaced angularly at the same intervals as the units marked on the scale 25; and on the underside of the arm 26, a tooth 33 is formed by pressing, shaped to fit snugly in the indentations 32 alternatively.

The indentations may be located on a line adjacent the edge 23 below the scale 25, or may be located elsewhere on the plate 16 and the tooth 33 correspondingly positioned. The tooth 33 is so located on the arm 26 that when engaged in one of the indentations 32, the top radial edge 29 of the arm 26 will be alined with one of the divisions of the scale 25, exposing immediately over the arm 26 the number denoting the range value of the particular setting of the arm 26.

On its lower edge, the arm 26 has an out turned flange or finger piece 34 adapted to be grasped between the thumb and forefinger, or pushed by any of the fingers or other members to move the arm upward or downward, when it is desired to change the setting of the sight, as will be explained hereinafter. The pivot base 27 of the elevation arm 26 has a number of nodules 35 formed on its under side distant from the pivot and opposite the major body portion of the arm and tooth 33, and bearing frictionally on the ear 24 so that the tooth is pressed firmly toward the plate 16, assuring firm engagement of the tooth in the indentations 32. The latter are preferably V-shaped in section, on the arc of the series, and radially elongated; and the tooth may approximate a knife edge, so that when it is brought over either sloping side of one indentation, it will tend to slip to a central position in the indentation.

While the indentations have been shown in the same number and spacing as the ordinals of the scale, the indentations may be multiplied, if desired, so as to position the edge 29 to indicate fractional parts of the main divisions of the scale, as well as the latter, in addition. To accommodate any additional fractional divisions, additional indentations may be in a parallel series and staggered in relation to the first ones.

In the present instance, the indentation 32 corresponding to the zero position of the arm 26 on the scale 25, is on a radius of the pivot parallel to the axis of the tube 15, and the tooth 33 is on the medial radius of the arm 26, so that the latter extends also parallel to the tube axis when at zero position. These relations of scale, indentation, and tooth to the tube or barrel of the weapon

are not arbitrary or essential as will appear, but are convenient in the present instance for a presentation of the invention.

Fixed on the pivot base 27 of the arm 26, there is a channelled foot piece or receiver 36, formed of flat sheetmetal, having outturned guides 37 thereon, parallel to the radius on which the tooth 33 is located, and including inturned lips or overhangs 38, parallel to the flat body portion of the piece and forming opposed deep grooves 39 thereunder. Midway of each guide an indentation 40 is formed in the extreme outer part of the guide extending into the groove slightly. The guides are equally spaced on opposite sides of the pivot of the arm 26, and the flat body portion of the receiver is apertured at 41 so as to clear the pivot rivet or screw 28, the lips 38 being likewise partly cut away at their middle parts in alignment with the aperture 41.

An eye-piece frame or carrier 42 is provided, stamped from sheet spring steel including a bifurcated shank 43 having spaced spring legs 44 provided with outturned flat feet 45 arranged in a common plane to which the shank is normal, and adapted, when moderately compressed, to slide respectively and simultaneously under the lips 38 of the receiver 36. The eye-piece 42 comprises a mounting for a lens 54 or the like which may be a polarizer of light formed in one piece from flat sheet stock, substantially of the form shown in Fig. 2.

The blank for the eye-piece mounting consists of a substantial rectilinear narrow strip of substantially uniform width throughout except for broadened portions 45' at respective ends thereof, and two ring side portions 46 near its middle, each having lateral flange extensions 47 at opposite sides. A narrow longitudinal flexible part 48 connects these wider parts at the middle of the piece. This blank is shaped to produce lateral rigid ring sides 46, each in the form of a segment of a circle conforming to the size of a lens or the like to be enclosed, the flange portions 47 being turned inward in parallel relation as retainers for an inserted lens 54 or other circular member. The flexible connection 48 is also shaped to the same circle, and short outer portions 49 of the blank longitudinally beyond the flanges 47 are likewise shaped, so that a complete ring 50 may be readily formed, adapted to be opened at the meeting of the parts 49 for emplacement or removal of a lens or other circular member 54 within the ring, to be embraced and retained by the ring and flanges 47 when the ring is closed. End portions of the blank outwardly of the meeting parts 49 are bent outwardly and radially so that they may be brought into close mutual parallel abutment to form the shank 43. One of the shank parts is drilled and tapped midlength and the other drilled to afford a larger aperture through which is inserted a headed screw 51 screwed into the other opening by which the two shank parts are secured together. Outwardly of the shank parts, the material of the blank is bent obliquely outward and at a short distance therefrom again bent inward to a similar degree so as to form parallel leg parts 44 when the shank parts are secured by the screw 51. Intermediate of the length of each of the broadened end portions 45, the outermost material of the blank is bent at right angles on a line at right angles to the direction of the adjacent leg, to form the foot 45. The outermost edges 52 of the feet are formed with notches 53 midway thereof of a

depth to fit the indentations 40 in the guides of the receiver. The extreme edge portions 52 of the feet are spaced slightly more than the bottoms of the opposed grooves 39, so as to require to be compressed toward each other in order to enter the grooves freely, and, after entry, requiring further compression in order to pass the indentations 40 far enough to permit the latter to enter the notches 53, when the feet will spring apart against the guides, engaging on each side of the indentations.

A lens device or other refractor 54 is provided, of circular form and of a diameter to be received snugly within the ring 50 and its flanges 47 when the shank parts 43 are brought together and secured. It should be understood that the axis of the ring 50, at zero position of the arm 26, is parallel to the axis of the tube 15.

This lens device may be a collimator lens, or system, adapted to project rearwardly collimated rays defining the image of a target brought into the line of sight of the instrument. The device carried by the ring 50 may alternatively be a small telescope projecting forwardly or at both sides of the ring. In one construction the inserted part has consisted of an axial light-polarizer crystal, or constructed polarizing material, having refracting rings concentric with the axis of the ring 50. Except so say that such collimating or polarizing or refracting material is available commercially from the Polaroid Co. of Cambridge, Massachusetts, the details thereof will not be described since none of the alternative devices comprise original features of the present invention.

In Figures 8 and 9, there is illustrated a modification of the invention in which the body 60, corresponding to the base 16 before described, is substantially of the same size and contour, but the upper stop 30 is omitted, and on the edge 23', corresponding to the arcuate edge 23 before described, a broad ear 61 is integrally formed in a plane with the remainder of the plate, a rectilinear, narrow slot 62 being formed therethrough, without, and tangent to, a geometrical projection of the arc defining the sector area 18' which corresponds to the area 18. There is no scale formed on this body 60, nor any indentations such as were on the plate 16. An aperture 22' corresponding to the one 22 is provided in the base ear 24'. This body is mounted permanently as before on the tube or barrel of the weapon on which it is to serve and the other sight elements applied as required.

There is provided a dial or scale plate 63 with pivot base 68 of a size and shape to include thereunder the base ear 24' and sector area 18' and to extend below the ear 31' (which is in substantially the same relative location with respect to the aperture 22 and the horizontal as the ear 31). The plate 63 has formed therein a slot 64 near its lower edge to receive the ear 31' loosely therethrough, the latter projecting beyond the plate 63 when the latter is so applied. The plate 63 is formed with an arcuate edge portion 65 coincident with the edge 23'; and is of a vertical extent to include the area corresponding to that occupied by the scale 25 of the plate 16.

On the edge 65 there is formed a broad radial tongue 66, having rectilinear upper and lower edges parallel to the mean radius of the tongue and with rounded or otherwise inclined corners 67. This tongue is positioned to align with the slot 62 and is bent at an angle of nearly 90 degrees

to the plate 63, so as to enter the slot 62 when the plate 63 is laid over the area 18' of the body 60. The extremity of the tongue 66 is bent outward to extend parallel to, and close to, the back side of the base plate 60, preventing withdrawal of the tongue from the slot except when the pivot end 68 of the dial plate is lifted away from the base 60. A pivot aperture 69 is formed in the end 68 to align with the aperture 22' and to receive pivot screws 70, substantially as in Fig. 3.

The width of the tongue 66 is such as to fit snugly at its edges against the ends of the slot 64—an important function, determining the proper calibration position of the dial plate with respect to the weapon. The plate 63 is provided in its upper part with a scale 25' the same as the one 25 before described and in the same arc concentric with the apertures 22' and 69, and below the scale a concentric series of indentations 32' similar to those 32 and in the same relation to the scale as before indicated.

With the device of Figs. 8 and 9, the same range arm 26 before described is used without change in the particular embodiment shown, the arm being laid over the dial plate 63 after the latter is positioned, and the pivot screws 70 engaged through the arm 26, plate 63 and plate 60, the head of the screw engaging the outer face of the arm to compress the latter and dial plate to proper operative position on the plate 60.

While the device is designed for use on a weapon fired from the shoulder, it may be used in other situations as well.

In use, the device being assembled in either form illustrated, when the elevation arm is set at zero on the scale 25 or 25', the weapon is used for point-blank firing, and when the target is at a distance requiring more particular elevational laying, the arm 26 is shifted upwardly until its upper edge 29 alines with the figure on the scale denoting the particular range involved. This moves the ring 50 around the axis of the pivot 28-70, the axis of the sight being tilted downward and causing the tube to assume the proper elevation when raised sufficiently at the muzzle to permit the marksman to view the target through the sight device 54 in the ring 50. With a good collimation of the rays defining the target as viewed through the element 54, the percentage of angular error for the ranges in which rocket launchers, grenade launchers and mortar devices are used, is small, and very quick laying of the weapon may be effected.

It is an advantage of a polarization or collimation device that accommodation of the eye of the marksman to the sight longitudinally of the weapon is automatically accomplished without adjustment of the eye-piece, since the eye of the user is spaced rearwardly of the sight at all times, it being unnecessary to apply the eye brow directly to the ring 50 or any other projecting mechanical part.

It is possible to provide a series of range scales similar to the one 25 on different arcs on the plate 16, or on the dial plate 63, each one calibrated for a different ammunition; but to avoid the extreme likelihood of error in selection of the proper scale, it is believed preferable to use the construction of Figs. 8 to 10. In such case, when a change of ammunition is decided upon the legs of the eye-piece frame are compressed and the feet drawn from the receiver 30 and the eye-piece laid aside. The screws 28-70 are now removed, together with the arm 26. The pivot end 68 of the dial plate 63 may then be lifted, the

tongue 66 drawn from the slot 62, and the plate 63 laid aside. Another dial plate of identical size, contour and structural features is substituted, differing in the specific calibration of its scale, which will be appropriate to the ammunition next to be used. After placing of the new dial plate, the arm 26 is returned to position thereover, and the screws 70 and 28 replaced, holding the new assembly in place, after which the eye-piece is returned to its place by sliding its feet into the receiver, until the notches 53 snap onto the indentation 40.

The aiming of the weapon with the new ammunition may then be proceeded with, as before described.

By substituting for the screw 70 a permanent stud set in the plate 60, and forming it with one element of a snap fastener the other element of which is incorporated in the base 27 of the elevating arm 26, the removal and replacement of the parts may be greatly expedited. It would then only be necessary to pull the base of the arm 26 from place by axial translative movement and secure it, when returned, by simple manual pressure in the opposite direction.

While the invention has been disclosed with great particularity in the best embodiment known to me, it will nevertheless be understood that various changes in the construction, arrangement and combination of parts, substitution of materials and substitution of equivalents mechanically or otherwise other than those specifically claimed may be made without departing from the spirit of the invention as more particularly set forth in the appended claims wherein I claim:

1. A gun sight comprising a base including a plate, a sight piece pivoted thereon on an axis normal thereto, a scale on the plate concentric with said axis, a pointer device movable with the sight piece, and a sight having an axis normal to the pivot axis mounted on said sight piece, said sight constructed to project an image of a target in line with said axis of the sight, said base plate comprising a planiform sheet metal blank having a lower portion bent upward at the rear to form a bracket arm for attachment to the underside of a tube or the like, the upper edge portion of the plate being extended for attachment at a tangent to the outer side of a tube or the like.

2. A sight of the character described comprising a support, a revoluble receiver thereon having a flanged diametrical guide thereon, a sight piece holder comprising a ring adapted to hold a sight piece therein and including a shank having resilient furcations formed with feet adapted to enter under respective flanges of the guide when tensioned.

3. The structure of claim 2 in which the sight piece holder comprises a narrow blank of resilient sheet metal having broadened extremities and at least one intermediate broadened part, the intermediate part of the strip being bent into a circular form constituting said ring, opposite edges in said intermediate broadened part bent inward to embrace the edge portion of an inserted lens or the like, the end portions of the strip being bent outward sharply in abutment at their junction with the circular part and connected to form said shank, the extremities being spaced apart, constituting said furcation.

4. A sight comprising a base member having a planiform plate, an arm pivoted thereon for sweep movement against the face of the plate, means to indicate the angular positions of the

2,445,314

9

arm on the plate, a receiver on the arm at the pivot axis of the arm, a sight mount having a shank portion removably engageable with the receiver, and constructed to extend on the pivot axis of the arm, and a ring fixed on its extremity in a plane coincident with said axis.

5. The structure of claim 4 in which said received is formed with a diametrical channel across the pivot axis, medial projections at the sides of the channel, said shank having spring loaded spaced compressible foot portions formed with opposite parallel sides recessed to receive said projection when the shank is in operative position on the receiver.

6. The structure of claim 4 in which said arm comprises a resilient plate, a series of spaced indentations concentric with the pivot formed in the base plate each being V-shaped in cross section and a knife edge member on said arm alined with said series and adapted to engage the indentations alternatively, said arm being stressed to press the tooth toward the base plate, whereby when the tooth engages the sloping side of an indentation it will tend to move to the middle of the indentation.

7. A sight comprising a body plate constructed for rigid attachment to the side of a weapon and having a pivot part and a distant slot transverse to a medial radius from the pivot part, a dial plate having a pivot part concentric with that of the body plate and having a radial tongue of a width to fit snugly in said slot when the dial plate is flat on the body plate, a pivot means extending through said pivot parts, a scale on the dial plate concentric with its pivot part, an arm pivoted on said pivot means and movable over the first two plates, and means to yieldingly hold the arm at stages of movement adjacent said scale.

8. The structure of claim 7 in which the pivot means of said arm consists of a plurality of axially aligned detachable parts, said parts being co-engaged with the said pivot parts of the body plate and dial plate.

9. A mount comprising a receiver support hav-

10

ing opposed overhanging parts and including opposed inward projections, and a mount device having spaced spring legs having respective out-turned parts to engage under respective overhangs and notched to receive said projections.

10. A sight comprising a base plate having a pivot member thereon, a dial plate adapted to be laid on the base and having a pivot part alined with the pivot member of the base, one of said plates having an opening distant from the pivot and the other having a projection to enter said opening, and a range arm pivoted on the dial plate at said pivot member.

11. The structure of claim 10 in which said projection has an outturned extremity arranged to engage the base to hold the outer part of the dial plate against separation until its pivot part is lifted from the base.

12. The structure of claim 10 in which said base and said dial plate are thin plates, said opening being an elongated slot extending at a substantial angle to an intersecting radius of the pivot part, and said projection is a tongue integral with its plate bent at an angle to extend through said slot, its extremity being bent outwardly to engage against the far side of the plate through which it is inserted, said tongue being of a width to engage snugly between the ends of the slot.
